SOFT PLASTIC FOOD PACKAGE

Leo Peters, Evanston, Ill.

Application July 29, 1950, Serial No. 176,634

3 Claims. (Cl. 99—171)

1

This invention relates to a changed-line pack for soft plastic foods. The invention is particularly useful in the packaging of soft plastic foods in consumer-size units within a retail-size package. The invention has a peculiar and unique advantage in packaging such foods in non-flat-sided shapes and other attractive shapes in which the upper portion of the molded food, after removal from the package, has a downwardly-inclined portion.

The particular problem which materials of this kind solves presents itself when: (1) substantially perpendicular lines are reversed or changed to horizontal direction, or (2) extremely sharp-edged contours are used in forming consumer-size compartments in retail packages for soft plastic foods and, (3) when the compartment liner is formed from a single, thin, homogeneous web of material used for packaging non-flat-sided shapes.

When the perpendicularly-inclined lines of such compartments constantly recede from top to bottom, the weight of the contents on these lines presents no problem because the lines follow the natural downward curve under pressure of the contents.

However, (1) when the perpendicular lines are reversed to point a substantial section of the compartment upward, or (2) when the perpendicular lines are changed to point a substantial section of the compartment in a general horizontal direction, then the weight of the contents acts as a deterrent to the upward sweep of this section of the compartment. And the thin flexible materials which must be used (in order eventually to remove the contents) will not maintain this reversed or changed direction unless they have sufficient structural strength of their own to resist the pressure of the contents.

Similarly if sharp-edged contours are required in the shapes, it is obvious that a relatively stiff material that will not bend easily under pressure from the contents is needed; that the soft, yielding, easy to fold and bend materials that are not of themselves self-supporting will not do.

In the solution of the above problem, I have suggested the use of certain types of material which, while flexible, nevertheless are sufficiently stiff to hold their shape without any other supporting medium. Such thin materials, such as metal foils, serve this purpose and because of their flexibility may be peeled away from the food. However, the use of such materials as metal foils presents in itself a problem in connection with the attachment of the liners to the

2

consumer-size compartments and the important need of maintaining the figured liners and contents completely out of contact with the compartment walls. If the liner is permanently secured to the compartment wall, it may be necessary to use an adhesive or other means for bonding the liner to the compartment wall, or it may be necessary with some foods to use slight hand pressures to push the foods out, or it may be necessary to have the compartment wall accompany the liner in covering unused portions of the food in the refrigerator. The above apparent requirements, which seem to be part and parcel of a liner that is permanently attached to the compartments, are frequently undesirable features, and therefore a problem presents itself on how to retain the advantages of a thin flexible liner while yet avoiding what are frequently its disadvantages.

20 A still further problem is presented in finding means for supporting the foods and in molding the same to reverse perpendicular lines in the lower portion of the mold while at the same time enabling the foods to be readily removed. In 25 the use of certain fairly stiff materials such as metal foils, there is a tendency for the food to cling to such supports and not to be removed with the same ease that they are removed from very flexible plastic and similar films. If a pack could be provided which would enable the 30 flexible film to be utilized for the major portion of the package while at the same time providing the stiffening support at the points where the perpendicular lines are to be reversed, the advantages of both types of packs could be obtained while at the same time utilizing the 35 flexible film as a suspension means for protecting the molded food products during shipment, etc.

40 An object of the present invention is to provide a package which solves the problems enumerated above and accomplishes the desired advantages. A further object is to provide a thin and stiff, yet flexible and peelable liner draped in reverse-line 45 or changed-line positions within and/or over the edge of the compartment and held thus by the inherent stiffness of the liner itself, the downward pressure exerted by the contents, and/or the bent and creased portion of the liner if the 50 same is draped over the edge of the compartment wall. A further object is to provide a thin and stiff, but flexible and peelable, liner or film which has sufficient thickness to be draped and molded in desirable shapes and stiffness to maintain it- 55 self in reverse-perpendicular line, and perpen-

icular-to-horizontal line positions against pressure from the weight of the contents, the film or liner being sufficiently malleable or flexible to peel off easily from the molded contents. A still further object is to provide a single film or liner of sufficient stiffness or rigidity to enable it to remain in whatever position it is bent so as to form and shape the soft plastic food introduced thereinto, such film, however, being bendable to enable it to be supported by a stiff support and removable freely therefrom, the liner or film being also readily pealable from the molded food contents. Yet another object is to provide a film or liner which grasps the compartment walls securely in reverse-line position without being sealed or bonded thereto, yet when inverted permitting the compartment walls free release. Still another object is to provide a package structure which is not bonded or otherwise permanently attached to the container walls, but which will yet hold the figured sides of itself and the contents suspended from, but out of contact with, the compartment walls. A still further object is to provide a package structure in which a highly flexible film is employed for suspending the product, the film being laminated with a stiffening support for reversing perpendicular lines or for changing the lines of the molded product, such combined structure permitting a ready release of the molded food product without marring or distorting the delicate lines thereof. Other specific objects and advantages will appear as the specification proceeds.

The invention is shown in illustrative embodiments by the accompanying drawing, in which—

Figure 1 is a perspective view of a package embodying my invention; Fig. 2, a vertical sectional view of one of the containers within the package; Fig. 3, a perspective view showing the removal of the tube from the supporting film or liner; Fig. 4, a similar perspective view showing the removal of the liner or film; Fig. 5, a perspective view of a modified form of container; Fig. 6, a vertical sectional view of the structure shown in Fig. 5; Fig. 7, a perspective view showing the removal of the food contents from the container illustrated in Figs. 5, 6 and 7; Fig. 8, a perspective view of another modified form of container; Fig. 9, a vertical sectional view of the structure shown in Fig. 8; and Fig. 10, a perspective view illustrating the removal of the food contents from the container illustrated in Figs. 8, 9 and 10.

In the form of the invention illustrated in Figs. 1 to 4 inclusive, I provide a tube support 10 which may be of cardboard, laminated board, plastic, molded pulpwood, or any suitable material. The purpose of the tube 10 is to provide a support for the structure which will be described.

Supported by tube 10 is a liner or film 11 which may be formed of metal foil such as, for example, aluminum, tin, or any of the metal foils. It may also be formed of treated papers which have sufficient stiffness to retain their shape while at the same time being bendable to permit the cup receptacle to be inverted for the removal of the food. For this purpose, the paper may be stiffened with materials applied thereto. Also plastic or thermoplastic films in stiffened form may be produced from polyvinylidene chloride, the polyamids, and various cellulose derivatives, as well as from combinations of these various materials.

The metal foils are particularly useful for this

purpose, since they can be molded, pressed, drawn, bent, and creased to hold almost any conceivable shape. Perpendicular lines can be reversed or changed to horizontal, and sharp lines and clear patterns can be made which will hold the soft plastic food in the desired shape without any other supporting means. At the same time, the foils can be withdrawn easily and peeled off the food without difficulty.

The liner 11 may be draped over the compartment or tube wall 10 and the upper edge of the liner may be bent outwardly and downwardly to provide an annular flange 12 which serves as a hook for securing the liner firmly upon the support 10. It will be understood that the support 10 may be square, rectangular, or of any desired shape, and that the material 11 may be readily bent to form a tight gripping flange 12 about the sides of the support. The weight of the contents bearing down on the liner keeps the liner firmly held upon the top of the support while at the same time the stiffness of the foil or other material forming the liner 11 causes its flange to grip the top of the support 10 and the gripping thereof around the top of the support keeps it from being pulled away from the support.

Because of the stiffness of the foil, the direction of the downward pull, which is substantially perpendicular, and the reversed direction on both sides of the wall, and the bent and creased position of the foil that grips the support, the foil itself will tend to break before loosening its grip upon the wall as long as the wall is in the normal upright position. At the same time, the figured portions of the liner and its contents are kept free from contact with the compartment walls, regardless of the jars and bumps received in transit and use.

When, however, the container is inverted to remove the contents, the foil slips loose and readily frees itself from the wall, under the weight of the food contents, thus leaving the liner alone, with the contents on the receiving dish 13, as illustrated in Fig. 3. The peripheral flange 12 at the top edge of the liner or film (which becomes the bottom edge when it is on the receiving dish 13) now provides a handle or gripping member which may be grasped by the consumer to peel the member 11 free from the contents. The foil may be retained to cover up unused portions of the food contents after the meal, the tube or support 10 being thrown away.

I prefer to provide the container with a closure or film cover 14, as illustrated best in Fig. 2, and preferably one side of the film is extended laterally and downwardly to provide a pull-tab 15. The cover 14 may be formed of metal foil, plastic, treated paper, or other suitable material, and may be secured to the top of the package, as illustrated, by the use of adhesive or other suitable means.

A plurality of the containers may be stacked one upon the other, as illustrated in Fig. 1, and adhesive tape 16 may be secured to the various containers so as to unite them in a single, rigid, retail package.

The tape 16 may, if desired, be run circumferentially of the contents so as to overlap adjacent containers and thus unite them. Any other suitable means for releasably uniting the containers may be employed.

In the operation of the structure, the consumer may peel away the top portion of the tape strips 16 to free the uppermost container. The pull-

tab 15 of the uppermost cover 14 may then be drawn to remove the cover. The container may then be inverted as illustrated in Fig. 3, to allow the liner 11 and the food contents to fall on the dish 13. The consumer may then grasp the outer edge portion 12 of the liner to remove it from the food contents, as illustrated in Fig. 4.

In the illustration shown in Figs. 5, 6 and 7, the liner or film 11a is preferably formed of thin, flexible material which is suspended from the top of the support 10 and is united to the top of the support by rubber cement or other suitable means. The film may be formed of thermoplastic or plastic material which flows under temperature or solvent conditions to provide a cup or container. For example, chlorinated rubber (Pliofilm), polyethylene, vinyl, acetate copolymers, vinylidene chloride, polyamids, and a large number of such well-known resins, may be used. Also, certain other sheeting material such as treated parchment papers, etc., may be employed. The above materials are used in a form which provides a highly flexible film and which suspends the food material in a resilient cup. However, the film retains mold lines. The great advantage of such film is that when the package 10 is inverted, as illustrated in Fig. 7, the film falls downwardly to permit a quick and clean separation of the food contents.

Since the flexible film 11a does not have sufficient stiffness to provide the support needed for a reverse central curve, as illustrated in Fig. 6, I secure to the central portion of film 11a a strip of metal foil 17 which tends to retain its shape against the pressure of the food contents. The strip 17 is bonded by adhesive or other means to the film 11a and a central portion 18 of the film 11a is maintained in the upwardly-curved direction illustrated. A cover 19 of transparent film may be sealed by a pressure sensitive adhesive to the edge of the thermoplastic film 11a, as illustrated in Fig. 6.

In the illustration given in Figs. 8, 9 and 10, a rectangular tube 20 is illustrated and a film 11b is secured thereto. The film 11b is sealed to the top of the support 20 and is provided with a cover 21 similar to cover 19 of the structure shown in Figs. 5 to 7 inclusive.

The film 11b may be formed of the same materials above described for film 11a, and to the bottom of the cup thus provided by the film 11a, I secure a plate 22 formed of metal foil or any other suitable material which is both stiff and flexible and which is useful in preparing a mold having upwardly- and downwardly-extending lines. In the illustration given, the plate 22 has a bird design and supports the film portion 23 immediately thereabove so as to give it the same configuration. The plate 22 is secured to the film 11b by adhesive or any other suitable means.

After the removal of the cover 21, the support 20 may be inverted, as illustrated in Fig. 10, to permit the removal of the food product, which falls upon the plate 22 therebelow. As illustrated further in Fig. 10, the film portion 23 permits the molded food to fall out of the compartment by its own weight, and the plate 22 permits a peeling action to take place so that the bird design is exposed and left intact on the food.

The new package is useful in the packaging of soft plastic foods such as butter, margarine, cheese, ice cream, gelatine, liver sausage, meat pastes, jellies, and a variety of similar products.

While in the foregoing specification, I have set forth a specific structure in considerable detail, it will be understood that such details of structure may be varied widely by those skilled in the art without departing from the spirit of my invention.

I claim:

1. In a soft plastic food package, the combination comprising a thin, flexible thermoplastic film providing a reversible cup, said cup having downwardly and inwardly tapering side walls and a bottom wall having upwardly-extending portions, a support disposed about said cup, said cup being suspended from said support so that said cup can be reversed and with the side and bottom walls of said cup out of contact with said support, a soft plastic food body within said cup conforming to its shape and pressing downwardly against the upwardly-extending portions of said bottom wall so as to tend to depress said upwardly-extending portions, and a relatively stiff reinforcing sheet laminated to the bottom wall of said pocket and overlying the upwardly-extending portions of said bottom wall while terminating short of said downwardly-extending side walls.

2. The combination of claim 1 in which said reinforcing sheet and the portions of said bottom wall covered thereby are provided with a figured design having raised portions, said design being impressed on the adjacent surfaces of said food body so that said food body presses downwardly on the raised portions of said design, said reinforcing sheet substantially preventing said raised design portions from being depressed under the weight of said food body.

3. The combination of claim 1 in which said bottom wall is provided with a centrally located upwardly-extending protuberance forming a recess in the adjacent surface of said food body so that said food body presses downwardly on said protuberance, said reinforcing sheet overlying said protuberance and substantially preventing it from being depressed by the weight of said food body.

LEO PETERS.
